UNITED STATES PATENT OFFICE

134,520

DESIGN FOR AN ELECTRICAL METER OR SIMILAR ARTICLE

George W. Cushing, Newark, N. J., assignor to
Weston Electrical Instrument Corporation,
Newark, N. J., a corporation of New Jersey

Application March 17, 1942, Serial No. 106,225

Term of patent 14 years

To all whom it may concern:

Be it known that I, George W. Cushing, a citizen of the United States, residing at Newark, in the county of Essex and State of New Jersey, have invented a new, original, and ornamental Design for an Electrical Meter or Similar Article, of which the following is a specification, reference being had to the accompanying drawings, forming part thereof, and wherein:

Fig. 1 is a perspective view of the electrical meter or similar article, showing my new design, as seen from the front;

Fig. 2 is a similar perspective view of the same as seen from the rear; and

Fig. 3 is a fragmentary horizontal section through the transparent cover plate and adjacent parts of the casing.

The dominant features of my design reside in the portion shown in full lines.

I claim:

The ornamental design for an electrical meter or similar article, as shown and described.

GEORGE W. CUSHING.
